DESIGN FOR A WOVEN ELASTIC TEXTILE FABRIC

Jack Julius Feldman, New York, N. Y.

Application May 12, 1939, Serial No. 84,935

Term of patent 3½ years

To all whom it may concern:

Be it known that I, Jack Julius Feldman, a citizen of the United States of America, residing in the city of New York, county of New York, and State of New York, have invented a new, original, and ornamental Design for a Woven Elastic Textile Fabric, of which the following is a specification, reference being had to the accompanying drawing, forming part thereof.

Fig. 1 on the drawing is an enlarged plan view of a woven elastic textile fabric showing my new design.

Fig. 2 is an enlarged plan view of the same surface as shown in Figure 1, the fabric being stretched.

The design is characterized by alternately raised and depressed surfaces as shown.

I claim:

The ornamental design for a woven elastic textile fabric, substantially as shown and described.

JACK J. FELDMAN.
